Bluefield, Va.

Application September 25, 1941, Serial No. 412,332

7 Claims. (Cl. 30—1)

This invention relates to guards for the protection of persons engaged in cutting materials and especially to protect a person from cuttings while cutting a railroad rail with a chisel or similar tool.

The primary object of this invention is the provision of a device of the above stated character which may be easily and quickly applied to the work and will be self-sustaining thereon and which will efficiently prevent cuttings from the tool from striking and injuring the person operating the tool.

Another object of this invention is the provision of a device of the character stated which will conform to the work with a gripping action to sustain itself in proper place on the work and has provision for exposing a portion of the work in such a way as to permit cutting thereof with a tool and at the same time confining the cuttings from the work to prevent such cuttings from escaping and injuring the operator and also will assist the operator in the movement of the tool over the work for the proper or desired cutting of said work.

With these and other objects in view as will become more apparent as the description proceeds, the invention consists in certain novel features of construction, combination and arrangement of parts which will be hereinafter more fully described and claimed.

For a complete understanding of our invention, reference is to be had to the following description and accompanying drawings, in which

Figure 1 is a side elevation, partly in section, illustrating a guard constructed in accordance with our invention and showing the same applied to a fragmentary portion of a railroad rail.

Figure 2 is a top plan view illustrating the device applied to the railroad rail.

Figure 3 is a transverse sectional view taken on the line 3—3 of Figure 1.

Figure 4 is a sectional view taken on the line 4—4 of Figure 1.

Figure 5 is a bottom plan view showing the device applied to a fragmentary portion of a rail.

Figure 6 is a perspective view illustrating the guard or protector removed from the rail.

Figure 7 is a transverse sectional view taken on the line extending through the cutting groove of the device.

Referring in detail to the drawings, the numeral 5 indicates a guard constructed of rubber or any other material suitable for the purpose and capable of having a limited flexion and is shaped to conform to the contour of a railroad rail 6,

that is, the guard 5 includes a portion 7 conforming to the ball 8 of the rail, a portion 9 conforming to the web 10 of the rail 6 and a portion 11 conforming to the base 12 of the rail.

5 The portions 7, 9 and 11 are of integral construction and have extending therethrough metallic reinforcing elements 13 of a flexible nature, however, having sufficient rigidity to assist in maintaining the guard in its proper shape.

The guard 5 is provided with a tool slot 14 extending vertically through the portion 9 into the portion 7 and also into the portion 11 of the guard. Said slot will permit a chisel or like tool to operate 15 against a selected area of the rail for the purpose of severing the rail transversely. The walls of the slot extending through the portion 9 are beveled, as shown at 15, for the purpose of permitting the tool to freely enter the slot and provide portions

20 16 along the slot which will readily flex for the purpose of permitting cuttings to work between the guard and the rail and enter channels or grooves 17 formed in the portion 9. The channels or grooves extend entirely the full length of the portion 9 and also extend into the part 7 and a portion of the part 11. The cuttings entering the channels or grooves may work downwardly toward the lower ends thereof and finally discharge out onto the ground adjacent the rail.

25 30 By referring to Figure 4 it will be seen that a tool working on the rail within the slot will frictionally contact the flexible portions 16 so that any cuttings leaving the rail by the action of the tool thereon will be prevented from flying directly outwardly against the operator and eliminate the possibility of injury from flying particles. Also, it will be seen that the tool entering and operating within the slot will be to some extent guided in its operation of cutting by the guard

35 40 being applied to the rail as shown and described heretofore in detail. This will greatly assist the operator in cutting the rail transversely on a selected line, as the guard can be applied to the rail exposing a portion of the rail where the cut is desired to be made.

A device of the character described and shown in the drawings will be extremely durable, easy to apply to a railroad rail at the place or point of location of the rail which may be upon a railroad bed so that cutting of the rail can be accurately and quickly carried out with a maximum amount of safety to the operator from flying cuttings.

50 55 While we have shown and described the preferred embodiment of our invention, it will be

understood that minor changes in construction, combination and arrangement of parts may be made without departing from the spirit and scope of the invention as claimed.

Having thus described the invention, what we claim is:

1. In a guard, a protecting member shaped to fit work to be cut by a hand operated tool and having a tool slot exposing a portion of the work to be cut and receiving the tool for action on said work and guidance relative thereto with only sufficient clearance for the tool to prevent hindrance of the movement of the tool and thereby permitting said member to act in preventing cuttings from the work striking an operator of the tool.

2. In a guard, a resilient member shaped to fit a railroad rail including a ball engaging portion, a web engaging portion and a base engaging portion, said member having a tool receiving slot exposing a portion of the rail to be severed permitting said member to act in preventing cuttings from the rail from striking an operator of the tool.

3. In a guard, a resilient member shaped to fit a railroad rail including a ball engaging portion, a web engaging portion and a base engaging portion, said member having a tool receiving slot exposing a portion of the rail to be severed permitting said member to act in preventing cuttings from the rail from striking an operator of the tool, and causing said cuttings to move between portions thereof and the rail, said member having channels opposing the rail to receive the cuttings.

4. In a guard, a resilient member shaped to fit a railroad rail including a ball engaging portion, a web engaging portion and a base engaging portion, said member having a tool receiving slot exposing a portion of the rail to be severed permitting said member to act in preventing cuttings from the rail from striking an operator of the tool, and causing said cuttings to move between portions thereof and the rail, said member having channels opposing the rail to receive the cuttings, opposed walls of said tool receiving slot being beveled and defining flexible portions for said member lying between the slot and the channels and normally contacting the rail and capable of

flexing to permit passing of the cuttings into said channels.

5. In a guard, a resilient member shaped to fit a railroad rail including a ball engaging portion, a web engaging portion and a base engaging portion, said member having a tool receiving slot exposing a portion of the rail to be severed permitting said member to act in preventing cuttings from the rail from striking an operator of the tool and causing said cuttings to move between portions thereof and the rail, said member having channels opposing the rail to receive the cuttings, opposed walls of said tool receiving slot being beveled and defining flexible portions for said member lying between the slot and the channels and normally contacting the rail and capable of flexing to permit passing of the cuttings into said channels, reinforcing elements embedded in said member at opposite sides of the tool slot.

6. In a guard, a resilient member shaped to fit a railroad rail including a ball engaging portion, a web engaging portion and a base engaging portion, said member having a tool receiving slot exposing a portion of the rail to be severed permitting said member to act in preventing cuttings from the rail from striking an operator of the tool and causing said cuttings to move between portions thereof and the rail, said member having channels opposing the rail to receive the cuttings, opposed walls of said tool receiving slot being beveled and defining flexible portions for said member lying between the slot and the channels and normally contacting the rail and capable of flexing to permit passing of the cuttings into said channels, reinforcing elements embedded in said member at opposite sides of the tool slot.

7. In a combined guard and guide, a resilient member applicable to a rail transversely thereof and shaped to conform to said rail and sustaining its position on the rail by a gripping action, said member having a tool slot for exposing a portion of the rail to be cut and provided with channels opposing the rail and lying at opposite sides and close to the tool slot to receive cuttings.
